UNITED STATES PATENT OFFICE.

JACOB L. HARDEN, OF NORTH PLATTE, NEBRASKA.

RESILIENT WHEEL.

1,256,479.

Specification of Letters Patent. Patented Feb. 12, 1918.

Application filed January 24, 1917. Serial No. 144,294.

To all whom it may concern:

Be it known that I, JACOB L. HARDEN, a citizen of the United States, and resident of North Platte, in the county of Lincoln and State of Nebraska, have invented certain new and useful Improvements in Resilient Wheels, of which the following is a specification.

The present invention has reference, generally, to resilient wheels.

It is well known in the art that the usual pneumatic tires, widely adapted for use on vehicles, especially, those of the motor driven type, while affording a certain amount of resiliency to the vehicle, are comparatively weak and unsubstantial by reason of the fabric construction thereof and hence, unsatisfactory, inasmuch as the same become unable to withstand the air pressure therein after use for a period of time, and as a consequence, permit "blow-outs" and various kindred disabilities, this being particularly true when the same are used in country wherein the roads or highways thereof are ill-graded and contain rock in quantity. Further, the tires, due to their construction, create considerable friction when the speed of the vehicle upon which they are mounted is increased, and the heat resulting therefrom will cause expansion of the air cushioning means therein, such expansion oftentimes resulting in "blowouts", owing to the weakened condition of the fabric construction.

It is therefore the dominant object of my invention to provide an improved resilient wheel which will obviate the above recited disadvantages, the wheel being so constructed as to render the same capable of absorbing such shocks or jolts delivered thereto during travel of the same, thus, serving to efficiently cushion the vehicle body and preventing fracturing or distortion of the various elements of the running gear thereof in addition to preventing the material jolting of the occupants of the same.

Another object of the invention is to provide a resilient wheel which can be used as the driving wheel for motor driven vehicles, the same being braced sufficiently to successfully withstand the driving torque delivered thereto from the power transmitting gearing of the vehicle.

A further object of the invention is to provide an arrangement of cushioning means

so positioned as to efficiently absorb shock or vibration in the wheels, the said cushioning means when under tension coöperating to brace each other, thus, insuring proper functioning of the same at all times and also the provision of a strong and durable construction.

Among other aims and objects of the invention may be recited, the provision of a wheel of the character mentioned with a view to compactness, and in which the number of parts are few, the construction simple, the cost of production small, and efficiency and operation high.

The invention consists, furthermore, in the novel arrangements and combinations of the parts of the wheel, as well as in the details of the construction of the same, all of which will be more fully described in the following specification, and then finally embodied in the clauses of the claims, which are appended to the specification and which form an essential part of the same.

The invention is clearly illustrated in the accompanying drawings, in which:

Figure 1 is a side elevation of my improved wheel;

Fig. 2 is a fragmentary longitudinal section therethrough;

Fig. 3 is a detail in perspective of the means for securing the arcuate cushioning spring to the inner rim;

Fig. 4 is a fragmentary transverse section through the wheel;

Fig. 5 is a similar section showing a slightly modified form;

Fig. 6 is a fragmentary side elevation detail in perspective of the inner rim;

Fig. 7 is a fragmentary top plan view of the inner rim showing the arrangement of one of the plunger rods therein;

Fig. 8 is a fragmentary detail in elevation with parts thereof broken away showing a slightly modified form of spring mounting; and

Fig. 9 is a fragmentary side elevation of yet another slightly modified form of the wheel construction.

Similar characters of reference are employed in all of the above described views to indicate corresponding parts.

Referring now more specifically to the several figures of the said drawings, my improved wheel may be stated to include the usual hub portion, designated by the nu-

meral 1, the hub portion in turn, being provided with a plurality of radially disposed spokes thereabout, which spokes I have indicated for the purpose of convenience by the numeral 2. Upon the outer ends of the said spokes 2 and about the same, there is arranged an inner rim 3, the same being provided upon its opposite peripheral faces, with wear compensating metal bands 4 and 5. To secure the wear compensating bands 4 and 5 to their respective rim portions 3, any fastening devices may be passed. In addition to forming the openings within the wear compensating bands 4 and 5 as well as the rim portion 3, I form therein in spaced apart relation from said first mentioned openings, longitudinal slots, the purpose of which will be subsequently apparent.

A second or outer rim 6 is arranged about the inner rim 3 in spaced relation therefrom and is provided with upon its inner peripheral face, a wear compensating band 7 while upon the outer peripheral face thereof, a tire 8, preferably formed of steel or the like 25 is disposed.

With a view toward providing means whereby the outer rim 6 will be resiliently supported upon the inner rim 3 together with its hub and spoke portions 1 and 2, respectively, I secure in spaced apart relation to the inner peripheral surface of the said rim 6, preferably intermediate their ends, a plurality of arcuate leaf springs generally indicated by the numeral 9, the said leaf 30 springs being maintained in fixed relation to the rim 6 through the medium of a plurality of connecting bolts 10, the bolts in turn, passing through suitable alined openings as formed in the rim portion 6, its wear compensating band 7 and the arcuate leaf 35 springs 9. It is to be noted, that the opposite extremities of the leaf springs 9 curve inwardly from the inner peripheral surface of the outer rim portion 6 and are pivotally engaged by pairs of connecting links 11, the said connecting links being apertured in proximity of their lower extremities whereby pivot pins or bolts 11' may be passed therethrough into engagement with suitable eyes formed by rolling the opposite 40 extremities of the said arcuate springs upon themselves. To secure the remaining or free ends of the links 11 to the inner rim portion 3, a plurality of pairs of clamping arms are 45 arranged about the said rim 3 and as will be noted, have their intermediate portions offset, whereby, they will snugly embrace the rim 3. It is to be noted that the offset portions of the clamping arms 12 and 13 are 50 of a length greater than the thickness of the inner rim 3. Therefore, to secure the same rigidly to the said rim 3, blocks 14 are arranged upon the under face of the rim 3 in suitable spaced apart relation, whereupon 55 bolts 14' are passed therethrough into the

rim. The blocks 14 as illustrated in Fig. 3 of the drawings, are shown detached from between the clamping arms 12 and 13, the position of said blocks being illustrated therebetween in dotted lines. With the 60 blocks 14 properly positioned with respect to the rim 3 the clamping arms are applied. Obviously, the blocks will correspond to the length of the offset portions of the said clamping arms, and as a consequence, the 65 same will snugly engage the rim 3. Openings are formed within those portions of the connecting links 11 as in proximity of the blocks 14, whereby pivot bolts 17 may be passed therethrough and through similarly 70 disposed openings formed in the said blocks 14. Fastening nuts 18 are then turned into 75 engagement with the screw threaded extremities of the bolts 17, to prevent lateral displacement of the same. Suitable openings are formed in the opposite extremities 80 of the clamping arms 12 and 13 and are adapted to receive therethrough connecting bolts 15 and 16, the said connecting bolts having turned into engagement therewith 85 suitable fastening nuts to prevent displacement of the same.

In addition to arranging the arcuate leaf springs 9 between the inner and outer rims 3 and 6, a plurality of radially disposed 90 rods or plungers 19 are passed through the same and are fixedly seated within suitable openings as formed in the rim 6. The remaining extremities of the plungers 19 are passed through certain of the slots formed 95 in the inner rim 3 in spaced relation from those openings through which the wear compensating band fastening devices are passed, the openings, as will be noted, being of a length sufficient to permit movement of the 100 plungers 19 when the sides of the outer rim 6 are moved upwardly upon depression of the same, that is when the rim 6 is moved eccentric of the hub 1. The plunger rods 19 are formed in sections, certain of the sections being engaged with the outer rim 6 while the remaining sections are disposed between the said rim 6 and the inner rim 3 and are connected to the first mentioned sections by unions 19', these unions being 110 turned into engagement with the oppositely screw threaded extremities of the bolt sections. Obviously, by forming the plunger rods 19 in sections, the same may be readily removed when it is desired to replace certain 115 of the active elements of the wheel construction or to replace sections of the bolts in the event of fracturing thereof. Expansible coiled springs 20 are arranged upon portions of the plunger rods 19 and have their 120 adjacent extremities bearing upon the opposite peripheral surfaces of the said rim 3, specifically, upon the outer faces of the wear compensating bands 4 and 5. To retain the outer springs 20 upon the plungers 125 130

19, bearing nuts 21 are turned into engagement with the screw threaded extremities thereof and as will be evident, engage the adjacent convolutions of the said springs. 5 Thus, when the arcuate leaf springs 9 are flexed by engagement of the wheel, that is, the outer rim 6 with the ground, the springs 20 will act in conjunction with the said springs 9 to efficiently absorb the shock and prevent the transmission thereof to the vehicle upon which the wheel is mounted.

10 Expansible coiled springs 22 are arranged directly beneath the opposite ends of the arcuate springs 9 and have their lower extremities seated within suitable bores as formed within the rim 6 and also serve as means to cushion such upward thrust as may be imparted to the said rim 6 during its travel over ruts, stones or the like as may be 15 encountered upon a roadway. I desire to have it understood that the expansible springs 22 in addition to serving as means for cushioning the movement of the opposite extremities of the arcuate springs 9 will 20 also serve to prevent undue vibration thereof, as would otherwise occur upon the rebound or return the same to their normal 25 position.

To prevent excessive flexing of the arcuate springs 9 together with the springs 20 as arranged about the various plungers 19, during depression of the outer rim 6, other plunger rods 23 are passed through the remaining slots formed within the inner rim 30 3 and have arranged about their oppositely projecting ends, expansible springs 24, these springs being maintained in proper position upon their respective portions of the plunger rods 23 by reason of enlarged bearing 35 40 head portions 25 formed upon the outer extremities of the plunger rods and bearing nuts 26 as turned into the engagement with the inner extremities of the plunger rods.

The bearing heads 25 formed upon the outer 45 extremities of the plunger rods 23 are normally arranged in spaced apart relation from the inner face of the wear compensating band 7 arranged upon the inner peripheral surface of the rim 6, but, upon material 50 depression of the said rim, will be caused to be engaged thereby and as a consequence, the springs 24 as arranged upon the outer extremities of the same will be placed under compression, thus, offering additional 55 resistance to the depression or upward thrust of the rim 6 and preventing undue flexing of the arcuate springs 9. Upon rebound or the return of the rim 6 to its normal position with relation to the rim 60 3, the plungers 23 will of course return to their normal positions also by reason of the springs 24 arranged upon the outer portions thereof. Those springs as arranged upon the upper portions of the plunger rods 23, 65 obviously, serve to maintain the rounded

bearing heads 25 in proper relation to the wear compensating bands 7 and insure proper operation thereof.

In the Fig. 9 I have shown a slightly modified form of my improved resilient or 70 spring wheel wherein, the springs 22 together with the plunger rods 23 and their respective springs 24 are eliminated, the arcuate springs 9 together with the springs 20 arranged upon the plungers 19 serving in 75 this instance as the vibration or shock absorbing means for the wheels. By omitting or eliminating the springs 22 and 24 from the construction of the wheel, it will be understood that the wheel may be readily 80 adapted for vehicles of less weight, since, should the vehicle not possess sufficient weight to permit the flexing of the various springs or active elements of the wheel construction when the same is subjected to 85 shock or vibration, the resultant jolt therefrom would not be fully absorbed.

Should it be desired to provide means whereby the springs 22 as arranged beneath the free ends of the arcuate springs 9 may 90 be placed under varying tension, thereby, insuring flexing of the same only when placed under predetermined pressure, I provide a novel means as disclosed in the Fig. 8 wherein, the rim 6 of the vehicle wheel is 95 provided with a plurality of radially disposed bores 28, the said bores being internally screw threaded and having turned into engagement therewith similarly threaded plugs 29, the upper extremities of the said 100 plugs being so shaped as to properly receive the lower convolutions, of the said springs 22 thereupon. With this construction, when it is desired to place the springs 22 under greater or less tension, the screw 105 threaded plugs 29 are adjusted to different positions within the internally threaded bores 28 accordingly.

From the foregoing, it will be obvious to workers in the art, that I have provided a 110 resilient wheel, which, by reason of its peculiar construction, will efficiently absorb such shock as may be transmitted thereto during its travel over rough or ill-graded roads, and further, by slight adjustment, may be 115 so regulated as to vary the tension of the shock absorbing means, thus, rendering the wheels particularly adaptable for vehicles carrying loads of different weights. Furthermore, it is to be noted, that when the outer 120 rim 6 is depressed, thereby, placing those spring or active elements as adjacent the point of engagement, under tension the spring or active elements as arranged upon the wheel at a point diametrically opposite 125 thereto will be placed under tension and hence, will efficiently brace the construction, thereby, preventing undue flexing or cushioning of the said spring or active elements and excessive movement of the outer rim 6 130

with relation thereto. Still further, the plungers 19 by reason of their mounting within the elongated slots formed in the inner rim portion 3, will be permitted to move sufficiently to allow movement of the side portions of the outer rim 6 with relation to the adjacent portions of the inner rim 3 while the plunger rods 23 will be also permitted to shift laterally to prevent binding of the same. Thus the shock absorbing or cushioning operation of the spring or active elements of the wheel construction will not be interrupted.

By varying the positioning of the bearing nuts 21 upon their respective plungers 19, the tension of the springs 20 arranged about the said plungers 19 may be varied, and thus, movement of the outer rim 6 toward the inner rim 3 may be regulated. It will be also understood in this connection, that the bearing nuts 26 as arranged upon the outer or screw threaded extremities of the plungers 23 may be also adjusted to vary the tension of the spring 24 arranged thereabout.

By reason of the engagement of the plunger rods 19 with the inner rim 3, it is to be appreciated that a connection between the inner and outer rims 3 and 6, respectively, is afforded, this connection serving to permit the wheel to be efficiently used as the driving wheel of motor driven vehicles.

I am aware that changes may be made in the various arrangements and combinations of the parts as well as in the details of the construction of the same without departing from the scope of my present invention as defined in the appended claims. Hence, I do not limit my invention to the exact arrangements and combinations of the devices and parts, as illustrated in the accompanying drawings and as described in the accompanying specification, nor do I confine myself to the exact details of the construction of the said parts.

I claim:

1. In a resilient wheel, an inner rim, an outer rim, a plurality of arcuate leaf springs interposed between said inner and outer rims, said springs being fixedly secured intermediate their ends to the outer rim and having their opposite ends pivotally secured to the inner rim, a plurality of radially disposed rods engaged with said springs and slidably engaged with the inner rim, coiled springs arranged about portions of said rods and bearing on the inner rim, means engaged with said rod for varying the tension of the coiled springs, a plurality of plungers slidably carried upon the inner rim, cushioning means on said plungers, and means engageable with said cushioning means for varying the tension thereof.

2. In a resilient wheel, an inner rim, an outer rim, a plurality of arcuate springs in-

terposed between said inner and outer rims, said arcuate springs being secured intermediate their ends to the outer rim and pivotally secured therein to the inner rim, radially disposed rods carried by said arcuate springs and slidably engaged with the inner rim, expandable coiled springs arranged upon portions of said rods and bearing on the inner rim, means engaged with said rods for varying the tension of said coiled springs, a plurality of radially disposed plunger rods carried by the inner rim and having certain of the ends thereof arranged in spaced apart relation from said outer rim, cushioning means arranged upon portions of said plungers and bearing upon the inner rim, and means engaged with the plungers for varying the tension of the cushioning means.

3. In a resilient wheel, an inner rim, an outer rim, a plurality of arcuate springs interposed between said inner and outer rims, said arcuate springs being engaged intermediate their ends with the outer rim and having their opposite ends pivotally engaged with the inner rim, a plurality of radially disposed rods carried by said arcuate springs and slidably engaged with the inner rim, cushioning means arranged about portions of said rods and bearing upon the inner rim, means engaged with said cushioning means for varying the tension thereof, a plurality of radially disposed plungers slidably carried by the inner rim and having certain of the ends thereof arranged in spaced apart relation from the outer rim, cushioning means arranged about portions of said plungers, means engaged with said plunger cushioning means for varying the tension thereof, and other cushioning means interposed between the opposite extremities of the arcuate springs and the outer rim, as and for the purpose set forth.

4. In a resilient wheel, an inner rim, an outer rim, a plurality of arcuate springs interposed between said inner and outer rims, said arcuate springs being secured intermediate their ends to the outer rim and having their opposite ends pivotally secured to the inner rim, and coiled springs arranged between the opposite ends of said arcuate springs and the outer rim, as and for the purpose set forth.

5. In a resilient wheel, an inner, an outer rim, a plurality of arcuate springs interposed between said inner and outer rims, said arcuate springs being secured intermediate their ends to the outer rim and having their opposite ends pivotally secured to the inner rim and arranged in spaced apart relation from the outer rim, springs arranged between the opposite ends of said arcuate springs and the outer rim, and adjusting means engaged with the springs, as and for the purpose set forth.

6. In a resilient wheel, an outer rim, a

- plurality of arcuate springs interposed between said inner and outer rims, said arcuate springs being secured intermediate their ends to the outer rim and having their opposite extremities arranged in spaced apart relation from the said outer rim and pivotally engaged with the inner rim, expandable coiled springs arranged between the opposite ends of the arcuate springs and the outer rim, a plurality of radially disposed rods carried by the arcuate springs and slidably engaged with the inner rim, cushioning means arranged about portions of said rods and bearing upon the inner rim, means engaged with said cushioning means for varying the tension thereof, a plurality of plungers carried upon the inner rim and having certain of the ends thereof arranged in spaced apart relation from the outer rim and adapted to be engaged thereby at times, cushioning means arranged about portions of said plungers, and means engaged with said last cushioning means for varying the tension thereof.
7. In a resilient wheel, an inner rim, an outer rim, a plurality of arcuate springs interposed between said inner and outer rims, said arcuate springs being secured intermediate their ends to the outer rim, blocks circumferentially spaced on the inner surface of the inner rim, clamping arms carried thereby, and links connecting said arms with the opposite ends of the arcuate springs.
8. In a resilient wheel, an inner rim, an outer rim, a plurality of arcuate springs interposed between said inner and outer rims, said arcuate springs being secured intermediate their ends to the outer rim, blocks circumferentially spaced on the inner surface of the inner rim, clamping arms carried thereby, links connecting said arms with the opposite ends of the arcuate springs, a plurality of radially disposed rods carried by said arcuate springs and slidably engaged with the inner rim, cushioning means arranged about portions of said rods and bearing upon the inner rim, and means engaged with said cushioning means for varying the tension thereof.

7. In a resilient wheel, an inner rim, an outer rim, a plurality of arcuate springs in-

terposed between said inner and outer rims, said arcuate springs being secured intermediate their ends to the outer rim, blocks circumferentially spaced on the inner surface 30 of the inner rim, clamping arms carried thereby, and links connecting said arms with the opposite ends of the arcuate springs.

8. In a resilient wheel, an inner rim, an outer rim, a plurality of arcuate springs in- 35 terposed between said inner and outer rims, said arcuate springs being secured intermediate their ends to the outer rim, blocks circumferentially spaced on the inner surface of the inner rim, clamping arms carried 40 thereby, links connecting said arms with the opposite ends of the arcuate springs, a plurality of radially disposed rods carried by said arcuate springs and slidably engaged with the inner rim, cushioning means ar- 45 ranged about portions of said rods and bearing upon the inner rim, and means engaged with said cushioning means for varying the tension thereof.

In testimony whereof, I affix my signature hereto.

JACOB L. HARDEN.

Copies of this patent may be obtained for five cents each, by addressing the "Commissioner of Patents, Washington, D. C."
